DIGITAL COMPUTER

John M. Farrell and Edward F. Weller, Jr., Detroit, Mich., assignors to General Motors Corporation, Detroit, Mich., a corporation of Delaware

Filed July 7, 1958, Ser. No. 747,067

13 Claims. (Cl. 315—84.6)

The present invention relates to digital computers and, more particularly, to a reversible digital computer capable of counting either negatively or positively.

In one form of digital computer a gaseous-discharge tube is provided which employs a center anode and a plurality of pins which are symmetrically arranged there-around. One group of these pins forms cathodes while the remaining pins form two groups of guides for transferring the discharge from one cathode to another. Normally, the discharge is maintained on one of the cathodes. However, upon the occurrence of an event to be counted, a series of pulses are applied to the guides which will cause the discharge to be transferred from one cathode to a succeeding cathode. By varying the sequence in which the guides are energized, the direction of transfer of the discharge may be controlled so that the tube is able to distinguish between positive and negative events. If it is necessary to record more events than can be handled by one tube, the tubes may be cascaded so that when the discharge has been completely cycled around one tube, a count is transferred to the succeeding tube. Although this permits counting in a positive direction, it has been extremely difficult, if not impossible, for the second and succeeding tubes to accurately distinguish between the occurrence of a positive count and a negative count in the first tube. Accordingly, heretofore, it has been impossible to cascade such tubes so as to form a reversible digital computer.

Therefore, it is now proposed to provide means for cascading a series of multicathode gaseous-discharge tubes so that a count may be transferred from one tube to a succeeding tube in either a positive or negative direction. More particularly, this is to be accomplished by interconnecting the output of one counting tube with the input to a succeeding counting tube by transfer means having a gaseous-discharge tube and a pair of gating circuits. The transfer tube includes a pair of cathodes interconnected with the input to the first counting tube so that the discharge therein will be maintained on the first cathode of the transfer tube if the discharge in the counting tube is moving in a positive direction and on the second cathode of the transfer tube if the discharge in the counting tube is moving in a negative direction. The two gating circuits are interconnected with the two cathodes and, as a result, will be actuated in response to the direction of the count in the first tube. These gates also interconnect the output of the first counting tube with the input of a succeeding counting tube. As a result, one or the other of the gating circuits will transfer a negative or positive count to the succeeding tube whenever the discharge in the preceding counting tube completes a cycle in a negative or positive direction respectively. It may thus be seen that any number of tubes may be cascaded so as to count any combination of positive and/or negative events.

In the two sheets of drawings:

Figure 1 is a schematic wiring diagram of a digital computer embodying the present invention.

2

Figure 2 is a series of wave forms present in various portions of the circuit of Figure 1 when counting a series of forward or positive events.

Figure 3 is a series of wave forms present in various portions of the circuit of Figure 1 when counting a series of reverse or negative events.

Referring to the drawings in more detail, the present invention is adapted to be embodied in a reversible digital counter or computer 11 for counting or recording a series of positive and/or negative events such as increments of forward and reverse movement of a member.

The present counter 11 comprises a trigger section 12 for producing pulses corresponding to the events to be recorded, a series of cascaded decade counting tubes 13 and 14 for recording the pulses, and also a transfer circuit 15 for transferring a negative or positive count from one decade tube 13 to the succeeding decade tube 14.

The present trigger section 12 includes a pair of photosensitive elements 16 and 17 arranged to scan the movement of a member (not shown). The photosensitive elements 16 and 17, which are interconnected with a voltage source 18 and load resistors 19 and 21, are arranged to produce voltage pulses across the resistors 19 and 21 for each equal increment of movement of the member. These pulses form pulse trains E₁ and E₂ (Figures 2 and 3). The photosensitive elements 16 and 17 are displaced so that the corresponding pulses in the two trains E₁ and E₂ will not occur simultaneously, but instead, will occur in a sequence dependent upon the direction of the movement of the member past the photosensitive elements 16 and 17. For example, when the member is moving in a forward direction and/or it is desirable to count in a positive direction, the pulses in train E₂ will precede the pulses in train E₁ (Figure 2). However, when the member is moving in a reverse direction and/or it is desirable to count in a negative direction, the pulses in train E₁ will precede the pulses in train E₂ (Figure 3).

The load resistors 19 and 21 are interconnected with the inputs 22—23 and 24—25 to a pair of substantially identical D.C. amplifiers 26 and 27 adapted to be triggered by the pulses in trains E₁ and E₂. The outputs 29 and 31 of these amplifiers 26 and 27 will comprise a second pair of pulse trains E₄ and E₅ consisting of a separate square wave pulse for each of the pulses across the load resistors 19 and 21. The sequence of the pulses in trains E₄ and E₅ are the same as the corresponding pulses in trains E₁ and E₂ and, although the duration of each of the square pulses is very short, the leading pulse in one train continues past the commencement of the corresponding pulse in the other train. However, the first pulse terminates prior to termination of the corresponding pulse in the other train.

The decade counting tubes 13 and 14 are of the so-called gaseous discharge multicathode glow transfer counting tube type. Each tube 13 and 14 comprises a central electrode which acts as the anode 32 and is surrounded by a plurality of cathodes. The cathodes in the first tube are numbers 1, 2, 3, 4, 5, 6, 7, 8, 9 and 10 and those in the second tube are numbers 10, 20, 30, 40, 50, 60, 70, 80, 90 and 100. Each cathode is interconnected with ground by a separate load resistor. In addition, interspersed between the cathodes 0 to 9 in the first tube 13 is a first group 33 of guide pins and a second group 34 of guide pins. These groups are only schematically shown in the drawings. All of the guide pins in the first group 33 are positioned on one side of the cathodes 0 to 9 and are interconnected with each other and with the output 29 from the first D.C. amplifier 26. The guide pins in the second group 34 are disposed on the opposite sides of the cathodes 0 to 9 and are all interconnected with each other and with the output 31

from the second D.C. amplifier 27. Since the maintaining voltage is substantially less than the breakdown voltage, the discharge will normally remain between some particular cathode and the anode. However, if a negative pulse from the first D.C. amplifier 26 is applied to the first group 33 of guide pins, the discharge will transfer from a cathode to the guide pin in the first group 33 closest thereto. If a second negative pulse from the second D.C. amplifier 27 is then applied to the second group 34 of guide pins and the first pulse terminated, the discharge will move to the adjacent guide pin in the second group 34. Upon termination of the second pulse, the discharge will move to the adjacent cathode and the tube 13 will have counted one positive or forward event. If the sequence in which the negative pulses are applied to the guide pins 33 and 34 is reversed the discharge will be transferred in the opposite direction from cathode to cathode around the tube.

It will thus be seen that the events as sensed by the photosensitive elements 16 and 17 will cause a transfer of the discharge in the tube 13 for each event and in a direction corresponding to the sequence of the events. If it is necessary to count to a greater amount than can be handled by a single decade tube 13, a second decade tube 14 may be cascaded with the first tube 13. The second tube 14 is substantially identical to the first decade tube in that it includes a plurality of cathodes 10, 20, 30, 40, 50, 60, 70, 80, 90 and 100 having first and second groups 35 and 36 of guide pins interspersed therebetween. Thus, whenever the discharge completely cycles around the first tube and settles on the number 9 or 0 cathode, a voltage will appear across the corresponding cathode resistor 37 or 38 to produce a control pulse for triggering the transfer of the discharge in the second decade tube from one cathode to an adjacent cathode.

In order to enable the second decade tube 14 to record a positive or negative count every time the discharge completes a cycle around the first decade tube in a positive or negative direction respectively, the transfer circuit 15 is provided. The transfer circuit 15 includes a multicathode discharge tube which functions as an add-subtract transfer tube 39. In addition, there is a forward gate 41 and a reverse gate 42 that are controlled by the transfer tube 39. The transfer tube 39 may be similar to the decade tubes. However, only a pair of adjacent cathodes 43 and 44 are connected to ground by load resistors 45 and 46. The first and second guide pins 47 and 48 between these cathodes are connected to the outputs 29 and 31 of the first and second D.C. amplifiers 26 and 27 respectively. All of the remaining cathodes and guide pins are not connected.

The forward gate 41 includes a control input 43' that is interconnected with the load resistor 45 for the positive or forward cathode 44 in the transfer tube 39. This input 43' will allow the gate 41 to normally be inoperative but when there is a predetermined positive potential thereon, as caused by conduction of the positive or forward cathode 44, the gate 41 will be conductive. A second input 49 thereto is interconnected with the load resistor 38 for the 0 cathode. This input 49 is adapted to receive a pulse and, if the gate 41 is operative, to transmit a corresponding pulse to the output.

The reverse gate 42 is similar to the forward gate 41 except the control input 51 is connected across the load resistor 45 for the negative or reverse cathode 43 so as to be responsive to the potential thereacross. The other input 52 is connected across the load 37 for the 9 cathode.

The output 53 of the forward gate 41 is connected to a first multivibrator 54 and the output 55 of the reverse gate 42 is connected to a second multivibrator 56. These multivibrators 54 and 56 each have a pair of outputs 58 and 59 that are connected to the inputs of a pair of multiplexes 61 and 62. Each multiplex 61 and 62 has one output 63 or 64 that is connected to

78 the guide pins in one of the groups 35 or 36 in the second decade tube 14.

It will thus be seen that, if the pulses in the pulse trains E₄ and E₅ are occurring in a positive or forward sequence, these pulses will cause the first decade tube 13 to count in a positive or forward direction. Simultaneously with the first count in the first decade tube 13, the pulses E₄ and E₅ will also cause the discharge in the transfer tube 39 to move to the positive or forward cathode 44. As long as the pulses are occurring in a positive sequence, the discharge will remain settled on the positive or forward cathode 44. As a result, the voltage E₆ across the resistor will rise to a predetermined positive amount and cause the positive or forward gate 41 to be operative. At the same time voltage E₇ across the negative or reverse cathode load resistor 45 will be zero and the negative or reverse gate 42 will be inoperative. Thus, whenever the discharge is transferring in a positive direction around the first decade tube 13 and settles on the 0 cathode, the voltage E₈ across the resistor 38 will change and produce a positive signal E₈ which will pass through the gate 41 and appear as E₁₀ at the input to the multivibrator 54. The output E₁₁ from the reverse gate 42 will remain zero. The outputs from the multivibrator will comprise E₁₂ which is a positive pulse and E₁₃ which includes a negative pulse and a positive pulse. These pulses will be fed into the multiplexes 61 and 62 and be inverted to form a negative pulse E₁₆ and a positive and negative pulse E₁₇. These pulses are applied to the first and second groups 35 and 36 of guide pins in the second decade tube 14. Since the pulse E₁₆ occurs first the discharge will transfer in a positive direction to the adjacent guide pin in the first group 35. The negative pulse in E₁₇ will then occur during the termination of the pulse E₁₆ and the discharge will move in a positive direction to the adjacent guide pin in the second group 36. When this pulse terminates the discharge will move in a positive direction to the adjacent cathode. Thus, whenever the discharge completes a positive cycle around the first decade tube 13, the discharge in the second decade tube 14 will advance one cathode.

It is, of course, apparent that if the pulses in trains E₄ and E₅ are occurring in a negative or reverse sequence, the reverse process will occur. That is, the pulses in E₄ and E₅ will cause the discharge in the transfer tube 39 to settle on the negative or reverse cathode 43. Thus E₆ will be zero and E₇ will be positive and forward gate 41 will now be inoperative and the reverse gate 42 operative. In the event the discharge in the first decade tube 13 is traveling in a negative direction and settles on the 9 cathode, a positive signal E₉ will appear at the input to the reverse gate 42 and be transmitted as E₁₁ to the multivibrator 56. This will trigger the multivibrator to produce a positive pulse E₁₄ and negative and positive pulses E₁₅. The multiplexes 61 and 62 will invert these and apply the pulses E₁₆ and E₁₇ to the guide pins 35 and 36 to transfer the discharge in the second decade tube 14 in a negative direction.

It is to be understood that, although the invention has been described with specific reference to a particular embodiment thereof, it is not to be so limited since changes and alterations therein may be made which are within the full intended scope of this invention as defined by the appended claims.

What is claimed is:

1. In a device of the class described, a first multicathode gaseous-discharge tube, having output electrodes, pulse means to cycle a discharge around said tube in either direction, control means for deriving a control pulse whenever said discharge reaches an output electrode of said tube, a second multicathode gaseous-discharge tube, transfer means connected directly with said pulse means and with said control means, said transfer pulse means being effective to cycle said second discharge

around said second tube in response to said control pulse and said pulse means in a direction corresponding to the direction of transfer in said first tube.

2. In a device of the class described, a first multicathode gaseous-discharge tube, having output electrodes, a pulse means to cycle a discharge around said tube in either direction, a second multicathode gaseous-discharge tube, means for deriving a control pulse whenever said discharge reaches an output electrode of said tube, a positive gate circuit and a negative gate circuit interconnected with said output electrodes and responsive to the direction of transfer of the discharge in said first tube whereby one or the other of said gate circuits will be operative in response to said direction, said operative gate being effective to transfer the discharge in said second tube in response to said control pulse and in a direction corresponding to the direction of transfer in said first tube, and means connected with said pulse means and gate circuits for applying control signals to said gate circuits to control the conduction thereof.

3. In a device of the class described, a first multicathode gaseous-discharge tube having output electrodes, pulse means to cycle a discharge around said tube in either direction, means for deriving a control pulse whenever said discharge reaches an output electrode of said tube, a gaseous discharge tube having at least a pair of cathodes responsive to said pulse means for transferring a discharge to one or the other of said last mentioned cathodes depending on the direction of transfer in said first tube, a second multicathode gaseous-discharge tube, gating means actuated by said pair of cathodes and responsive to said control pulse for transferring the discharge in said last tube in a direction corresponding to the direction of discharge transfer in said first tube.

4. In a device of the class described, a first multicathode gaseous-discharge tube having output electrodes, pulse means to transfer said discharge from cathode to cathode around said tube in either direction, a second multicathode gaseous-discharge tube, means for transferring a discharge from cathode to cathode around said second tube in either direction, means for deriving a control pulse from said first tube whenever said discharge completes a cycle and reaches an output electrode of said tube, a positive gate circuit, a negative gate circuit, said gate circuits being interconnected with the input to said second tube and alternatively actuated in response to the direction of transfer in said first tube, said operative gate circuit being responsive to said control pulse for transferring the discharge in said second tube to an adjacent cathode and in a direction corresponding to the direction of transfer in the first tube, and means connected with said pulse means and gate circuits for applying control signals to said gate circuits to control the conduction thereof.

5. In a device of the class described, a first multicathode gaseous-discharge tube having a plurality of cathodes, pulse means to transfer said discharge from cathode to cathode around said tube in either direction, a second multicathode gaseous-discharge tube having a plurality of cathodes, means for transferring a discharge from cathode to cathode around said second tube in either direction, a gaseous-discharge tube having at least a pair of cathodes responsive to said pulse means for transferring a discharge to one or the other of said last mentioned cathodes depending on the direction of transfer in said first tube, a positive gate circuit, a negative gate circuit, said gate circuits being operatively interconnected with said pair of cathodes and with said first and second tubes for transferring the discharge in said second tube in a direction corresponding to the direction of transfer in said first tube whenever the discharge therein completely cycles around the first tube.

6. A reversible electronic counter comprising a first counting tube having a plurality of discharge cathodes, means for sequentially transferring said discharge from

one cathode to an adjacent cathode on either side thereof, said means being responsive to a pair of pulse trains for transferring said discharge from one cathode to an adjacent cathode as a result of a pulse in each train with the direction of transfer being determined by the sequence of the pulses in said trains, a second tube having a first and second cathode, and means responsive to the sequence of the pulses in said pulse trains for retaining said discharge on one or the other of said cathodes depending upon the sequence of the pulses in said trains, a second counting tube having a plurality of discharge cathodes, means responsive to the discharges in said first and second tubes for transferring the discharge in said second tube to an adjacent cathode whenever the discharge in said first tube completes a cycle and in a direction determined by whether said first and second cathodes are operative.

7. A reversible electronic counter comprising a first counting tube having a plurality of discharge cathodes and output electrodes, means for sequentially transferring said discharge from one cathode to an adjacent cathode on either side thereof, said means being responsive to a pair of pulse trains for transferring said discharge from one cathode to an adjacent cathode as a result of a pulse in each train with the direction of transfer being determined by the sequence of the pulses in said trains, means for deriving a control pulse whenever said discharge reaches an output electrode of said tube, a second tube having first and second cathodes, and means responsive to the sequence of the corresponding pulses in said pulse trains for retaining said discharge on one or the other of said cathodes depending upon the sequence of the pulses in said trains, a second counting tube having a plurality of discharge cathodes, a first gate circuit and a second gate circuit interconnected with said first and second cathodes to be actuated by whether the discharge is on the first or second cathode, said gate circuits being effective to transfer the discharge in said last mentioned tube from one cathode to another cathode therein in response to said control pulse and in a direction corresponding to the sequence of said pulses.

8. In a device of the class described, a first multicathode discharge tube having a pair of output electrodes, pulse means to cycle a discharge around said tube in either direction, a second multicathode discharge tube having control electrodes, means for deriving a control pulse whenever said discharge reaches one of said pair of output electrodes of said first tube, a positive gate circuit and a negative gate circuit connected with said output electrodes and with the control electrodes of said second tube, and control means connected with said pulse means and said gate circuits for controlling the conduction of said gate circuits in response to the voltage waveform of said pulse means.

9. The circuit according to claim 8 wherein the control means comprises a third multicathode discharge tube.

10. In a device of the class described, a first multicathode discharge tube having a pair of output electrodes, pulse means to cycle a discharge around said tube in either direction, a second multicathode discharge tube having control electrodes, means for deriving a control pulse whenever said discharge reaches one of said pair of output electrodes of said first tube, positive and negative gate means connected with said output electrodes and with the control electrodes of said second tube, and control means operated by said pulse means for controlling the conduction of said gate means.

11. In a device of the class described, a first multicathode discharge tube having a pair of output electrodes, pulse means to cycle a discharge around said tube in either direction, a second multicathode discharge tube having control electrodes, positive and negative gate means connecting the output electrodes of said first discharge tube with the control electrodes of said second discharge tube, and means for controlling the conduction of said

gate means in accordance with the output of said pulse means.

12. In a device of the class described, a first multicathode discharge tube having a pair of output electrodes, pulse means to cycle a discharge around said tube in either direction, means for deriving a control pulse whenever said discharge reaches one of said pair of output electrodes of said first tube, a second multicathode discharge tube having control electrodes, and controllable transfer means controlled by said pulse means for transferring said control pulse to the control electrodes of said second discharge tube.

13. In a device of the class described, a first multicathode discharge tube having a pair of output electrodes, 15

pulse means to cycle a discharge around said tube in either direction, means for deriving a control pulse whenever said discharge reaches one of said pair of output electrodes of said first tube, a second multicathode discharge tube having control electrodes, and controllable transfer means controlled by said pulse means for transferring said control pulse to the control electrodes of said second discharge tube.
